CLAIM

The ornamental design for a hand tool for removing and replacing spiral lock washers from and into annular grooves, as shown.

DESCRIPTION

FIG. 1 is a perspective view of a hand tool for removing and replacing spiral lock washers from and into annular grooves embodying my new design;

FIG. 2 is a top plan view thereof;

FIG. 3 is a side elevation thereof;

FIG. 4 is a bottom plan view thereof;

FIG. 5 is a right elevation view thereof; and

FIG. 6 is a left elevation thereof.
